CLAIM

The ornamental design for an iliac plate for posterior pelvic fracture stabilization apparatus, as shown and described.

DESCRIPTION

FIG. 1 is a top plan view of an iliac plate for posterior pelvic fracture stabilization apparatus showing my new design;

FIG. 2 is a side elevation view thereof;

FIG. 3 is an end elevation view thereof;

FIG. 4 is an end elevational view of an iliac plate for a posterior pelvic fracture stabilization apparatus shown in use, the broken line showing of the compression rod and a second iliac plate is for illustrative purposes only and forms no part of the claimed design;

FIG. 5 is a bottom plan view of the iliac plate of FIG. 1;

FIG. 6 is a side elevational view opposite that shown in FIG. 2; and,

FIG. 7 is an end elevational view opposite that shown in FIG. 3.

FIG. 1

FIG. 2

FIG. 3

FIG. 4

FIG. 5

FIG. 6

FIG. 7
